UNITED STATES PATENT OFFICE.

JAMES R. C. WATSON, OF PHILADELPHIA, PENNSYLVANIA.

WINDOW SHIELD.

Application filed June 9, 1926 Serial No. 114,695.

My invention relates to new and useful improvements in a window shield, particularly adapted for use in connection with vehicles, such as automobiles, street and railway cars and locomotive cabs, and has for its primary object to provide means for blowing a continuous stream of air of large volume in front of the vehicle window, wind shield or the like, so as to prevent it from being covered with snow or rain.

Another object of the invention is to provide means for supplying a large volume of air economically and continuously, if necessary, rather than spasmodically, whereby a window or its equivalent may be kept clear in stormy weather.

With these ends in view, this invention consists in the details of construction and combination of elements hereinafter set forth and then specifically designated by the claims.

In order that those skilled in the art to which this invention appertains, may understand how to make and use the same, I will describe its construction in detail, referring by numerals to the accompanying drawings forming a part of this application, in which:

Fig. 1, is a fragmentary sectional view of an automobile, illustrating one method of using my invention.

Fig. 2, is an enlarged sectional view of the upper portion of Fig. 1 to illustrate a detail of construction.

Fig. 3, is a face view of one of the imperforate plates used for closing one of the inlets to the blower.

Fig. 4, is a face view of the perforate plates which act as strainers to prevent large particles of foreign matter entering the air conduits.

Fig. 5, is a face view of a modified form of blower.

Fig. 6, is a plan view thereof.

Fig. 7, is a front elevation of the vehicle shown in Fig. 1 with parts eliminated and portions broken away and shown in section to illustrate the location and arrangement of the different elements.

Fig. 8, is a plan view with a portion broken away, of another form of blower.

Fig. 9, is a sectional elevation of still another form of blower.

Fig. 10, is a fragmentary front elevation of a railway car, illustrating an application of my invention.

Fig. 11, is a sectional view thereof.

Fig. 12, is a horizontal sectional view of the same.

In carrying out my invention as embodied in Figs. 1, 2 and 7, 15 represents an automobile provided with the usual crank case 16 of an engine 17 and a transmission casing 18, all of which are covered by the hood 19. In this particular embodiment of my invention, the automobile is provided with the usual dash 20 and a secondary dash 21 spaced therefrom, 60 while above this is the usual cowl 22, and a supplementary inner cowl 23 spaced from the main one, and said supplementary cowl may have a passageway 24 therein, which is controlled by a closure 25 hinged or otherwise 65 mounted under said supplementary cowl.

Projecting from the main cowl 22 is a main wind shield 26, while from the supplementary cowl 23 projects a supplementary wind shield 27 spaced from the primary one, 70 as plainly shown in Fig. 1, all of said parts coacting to form an air conduit 28, with an outlet 29; above or at the outer portion of the main wind shield, which outlet is controlled by a closure 30 held in different adjusted positions by a fastening means 31, such as a set screw carried by the closure and coacting with the slotted bracket 32, and in a similar manner the conduit 28 also leads to another outlet 33 located above or in the outer 75 portion of the supplementary wind shield, and may be directly opposite the outlet 29, and like the latter, the outlet 33 is controlled by a closure 34 hinged or otherwise mounted on a portion of the vehicle, and carrying fastening means 35 coacting with the slotted bracket 36. The brackets 32 and 36 may be mounted at the sides of the wind shields, or as shown, one may be secured to the visor and the other to the vehicle roof. 80

The lower part of the air conduit is closed by a transverse partition 37, and the space between the dashes may be divided by another partition 38 so as to separate one part from the other, and make one of these parts 100 airtight; while the dashes may have holes therethru in the other part for the passage of a choke valve rod, ignition cables and the like.

Within the space between the two dashes 105 is mounted a blower 39, and it is to be understood that wherever the term "blower" is used, it is to include fans or other air agitating instrumentalities in contradistinction to pumps or compressed air apparatus, and 110

said blower is positioned in alignment with an opening 40 in the main dash and a similar opening 41 in the supplementary dash, so that air may be drawn into the conduit either 5 from the outside or inside of the vehicle.

Over both of the openings are disposed suitable framework spiders 42, being secured in place by fastening means 43', and on these spiders are detachably mounted the perforate 10 plates or discs 43, by means of key hole slots 44 which register with rivets or equivalent attaching means 45, and, when found desirable, either opening may be closed by the use of an imperforate plate 46, also having key 15 hole slots 47 for coaction with the rivets 45.

The shaft of the blower has a gear 48 thereon to mesh with the gear 49 on the vertical shaft 50, the latter carrying one member of a clutch 51, while the other member thereof 20 is mounted on a stub shaft 52 upon which is mounted a gear 53 meshing with a gear 54 on the cam shaft 55, or other equivalent movable part of the motor. The clutch may be controlled by a bell crank lever 56 which, in 25 turn, is operated by a suitable actuating mechanism 57, so arranged as to be accessible to the vehicle operator.

From the foregoing description it will be apparent that when the motor is running and 30 the clutch is thrown in, the blower 39 will revolve and cause air to blow through the air conduit 28, being drawn into said conduit either through the opening 40 from beneath the hood of the vehicle, to which I refer as 35 the outside of the vehicle, or it may be drawn from the inside of the vehicle through the opening 41, depending upon which opening is closed by the imperforate plate 46, although both of the openings might be left uncovered, 40 and air drawn from both places at once. The air passing through the conduit with considerable force will be expelled through the outlet 29 and then baffled or guided by the closure 30 so as to direct the stream of air 45 down across the outside of the main wind shield 26, and any rain or snow coming within the region of this outside stream of air will be carried along with it and prevented from reaching the wind shield, and 50 therefore the latter is always kept clear so that the vision of the operator will be unobscured.

In order to overcome any likelihood of the 55 outside stream of air being deflected by side winds, deflecting wings 58 may be placed at both sides of that portion of the wind shield over which the outside stream of air passes.

Where the wind shield is provided with the 60 secondary opening 33, the device may be used for ventilating or cooling the vehicle as the closure 34 might be opened and the outlet 29 closed, permitting a stream of air to circulate within the body of the vehicle.

In Figs. 10, 11 and 12, I have shown the invention applied to another form of vehicle

herein illustrated as a street or railway car 59, provided with lookout or vestibule windows 60 and above any or all of these windows is arranged the outlet end of an air conduit 61 leading from a blower 62. The blower is 70 supported on the vehicle in any suitable manner, and to the shaft 63 of the fan 64 is attached an electric motor 65, and it is to be understood that the casing of the blower is provided with the ordinary air inlet 66, and 75 may have an opening 67 controlled by a closure 68.

At the outlet end of the conduit 61 is located a closure 69, which also acts as a deflector or baffle for deflecting the current of 80 air issuing from the conduit across the lookout or vestibule window or windows, said closure being hinged or otherwise mounted for movement, and may be held in different adjusted positions by the operating mechanism 70.

If found desirable, deflecting wind shields 71 may be provided one on each side of the path of travel of the air stream issuing from 85 the conduit.

In stormy weather, the device may be placed in operation, so that a stream of air will be projected in front of the lookout or vestibule window or windows to prevent rain or snow from adhering thereto, and as the 90 air which is used may be drawn from the interior of the car, its temperature can be higher than the outside air, and so prevent the formation of ice on the window. During such times as the device is not being used for 100 keeping the windows clear, the closure 68 may be opened, and the conduit 61 closed by the closure 69, thus causing a circulation of air within the vehicle.

In Figs. 5 and 6, I have illustrated another 105 form of blower, in which a casing 72 is provided, and this is open at both ends with the shaft 73 of a motor 74 projecting into the same with ordinary fan blades 75 mounted thereon within the casing.

In Fig. 8 a blower is illustrated in which the casing 76 is similar to the one shown in Fig. 12, but has only an air inlet 77, with the blower fan 78 located within the casing; in other words, the secondary outlet is eliminated.

In Fig. 9, a casing 79 is shown having a plurality of outlets 80 so that air moved by the blower fan 81 within the casing may be distributed to a number of different points.

Of course I do not wish to be limited to the exact details of construction as herein shown as these may be varied within the limits of the appended claims without departing from the spirit of my invention.

Having thus fully described my invention, what I claim as new and useful is:

1. The combination with a vehicle provided with a window, of a blower, a conduit leading from said blower to a point above

the window; a closure for the outer end of said conduit adapted when open to deflect the stream of air issuing from the conduit downward across the window; and wings on both 5 sides of the path of travel of said air stream to prevent deflection of the latter by side winds.

2. The construction set forth in claim 1, wherein the blower is provided with a secondary outlet controlled by a closure whereby an air stream may be projected into the 10 vehicle.

3. In combination, a vehicle having a pair 15 of walls adjacent each other to form a portion of an air conduit; a pair of windows spaced apart to form a continuation of said air conduit; an outlet above each window; means to control said outlets; a blower located within 20 the conduit and communicating with the interior and exterior of the vehicle; means to close either of said communications for selectively drawing air into the conduit; and means controlling each outlet opening to selectively control the distribution of air passing 25 through the conduit.

4. The structure set forth in claim 3, wherein in a passageway is provided from the air conduit to the lower portion of the vehicle; and means to control the passage of air through 30 said passageway.

5. In a device of the character stated, the combination of a motor-driven vehicle in-

cluding the usual engine and associated elements, the body of said vehicle including a main dash having an inlet opening, a secondary dash having an inlet opening and spaced from the main dash; a secondary cowl projecting from the secondary dash and spaced from the main cowl and also having a passageway therethrough; a main window 40 arranged above the main cowl; a secondary window arranged above the secondary cowl and spaced from said main window, all of said parts coating to produce an air conduit having outlets above the windows; a blower 45 provided with a shaft journaled within the conduit in the region of the inlets; means for transmitting motion from a suitable part of the vehicle motor to said blower; means to control the motion transmission means; closures for the outlets, one of which is adjustable to deflect a stream of air issuing from the conduit across the outside of the main window; a closure for the passageway through the secondary cowl for controlling the passage 50 of air from the conduit into the lower portion of the vehicle body; and means for closing either of the inlets to the conduit to selectively draw air into the conduit from the interior or exterior of the vehicle. 55

In testimony whereof, I have hereunto affixed my signature.

JAMES R. C. WATSON.
